UNITED STATES PATENT OFFICE.

JAMES P. QUAM, OF CHICAGO, ILLINOIS, ASSIGNOR TO EDWARD M. ADAMS, OF CHICAGO, ILLINOIS.

AIR CLEANER.

Application filed October 4, 1920. Serial No. 414,700.

To all whom it may concern:

Be it known that I, JAMES P. QUAM, a citizen of the United States of America, and a resident of Chicago, county of Cook, State of Illinois, have invented certain new and useful Improvements in Air Cleaners, of which the following is a specification.

This invention relates to air-cleaning apparatus particularly useful for separating 10 dust and heavier particles from air, for use in internal combustion engines. The invention more particularly relates to improvements in centrifugal separators which are driven by a rotor propelled by the current of 15 air which is drawn by the engine through the carbureter.

The main object of the invention is to produce a vortex of all the air passing through the device, and which vortex is of considerably 20 greater diameter than the driving rotor and consequently develops an increased velocity and centrifugal action whereby its separating effect is improved over the ordinary fan type of separator. A further purpose 25 of the invention is to provide a vortex producing element which is of larger diameter and separable from the rotor which drives it. A further object of the invention is to provide improved means for decreasing 30 the motion of the air near the area where the separated dirt collects and to provide a compartment for the collection of the dirt which is protected from the motion of the separating vortex.

The objects of the invention are accomplished 35 by the device as shown in the accompanying drawings in which—

Fig. 1 shows the improved air cleaner in vertical section.

Fig. 2 is a sectional detail showing the inlet to the dirt receptacle.

It is well known that the engines of automobiles and tractors, particularly when driven through dusty localities, are very 45 much injured by dust, even sand making its way into the engine cylinders. For the purpose of effectually separating the heavier particles carried by the incoming air, the present invention comprises a more or less

semi-spherical casing having an air inlet at 50 its upper end and an outlet to the engine carbureter at its lower end. At one side of the device provision is made for collecting the dirt which is separated from the air by centrifugal action. Centrally located within 55 the casing is a rotor having fan-shaped blades and rigid with this rotor is a conical hood which has upwardly extending radiating flanges for producing the desired whirling motion of the entering air. The hood being 60 of considerably greater diameter than the rotor, causes the air to whirl around the inner surface of the casing at a considerable increase in velocity over its traveling motion through the inlets and outlets of the device. The centrifugal action on heavy particles in the air causes them to travel outwardly and downwardly toward the curved 65 inner surface of the casing and around the edge of a projecting disk rigidly secured in the casing somewhat above the bottom of its floor. The function of this disk is to provide a comparatively dead air space near the point of outlet of the collected dirt which drops through an aperture below the disk 70 into a jar suspended from the casing.

The drawings show a casing 1 of a somewhat semi-spherical form having a floor 2 and an inlet for air 3 centrally located at its upper end and an outlet 4 for dirt at one side of its floor. A projecting lip 5 on the floor 2 at one side of the outlet serves to direct the dirt downwardly into a jar 6, which is threaded into a socket 7 formed in floor 2. An elbow-shaped conduit 8 cast with the 80 floor 2 conducts the cleaned air from within the casing 1 toward the carbureter. This elbow 8 has spider arms 9 for supporting a vertical post 10 which serves as a bearing for the rotor 11 and the flanged hood impeller 12 85 rigid therewith. A cap 13 which is screwed on to a sleeve 14 serves to secure the hood 12 to the sleeve 14 on which sleeve the rotor 11 is also mounted at its lower end. Cap 13 contains a ball 15 which sustains the weight 90 of the rotor and connecting parts by resting on the upper end of post 10. The radial flanges or fins 16 on the upper surface of the

- hood 12 are shown as angle bars riveted to the hood. A fixed disk 18 is mounted on the elbow 8 somewhat above the floor 2 of the casing 1, for the purpose of separating the 5 interior of the casing into two compartments having communication around the outer edge of the disk and for protecting the compartment below the disk against the action of the whirling air above it.
- 10 In the operation of the device, the air drawn through the elbow 8 by the suction of the engine, by engaging the inclined blades of the rotor effects rotation of the latter and the hood 12 rigid therewith. The down- 15 wardly traveling vertical column of air entering the inlet is twisted by the action of flanges 16, this whirling or twisting motion being very much increased in velocity as the air travels downwardly between the casing 20 1 and the hood 12. The dirt which is thrown outwardly by the whirling air travels downwardly along the curved and outwardly inclined inner surface 17 of casing 1. The momentum of the dirt as it falls below the 25 plane of disk 18 carries it against the beveled lip 5 where it drops into the collecting jar 6.
- The whirling motion of the air continues as it travels inwardly from the surface 17 toward the rotor 11 and accordingly strikes 30 the rotor blades at a suitable angle for maintaining the maximum velocity of the rotor. Due to this cause and that the load on the rotor is very light, the latter tends to race and thereby effects a very considerable centrifugal action in view of the velocity of the 35 incoming air.
- Since the element for producing the whirling action of the air is made to conform to and lies close to the walls of the casing, the 40 incoming air has, in addition to its whirling motion, an increased velocity in a downward direction with respect to its rate of travel in the comparatively large area exterior of the upwardly projecting conduit or elbow 8.
- 45 With this arrangement the heavier particles are thrown out and down while the space below the rotating hood permits gravity to act effectively in assisting to settle the dust, the air in this space traveling upwardly at 50 a slower rate.
- Although but one specific embodiment of this invention has been herein shown and described, it will be understood that numerous details of the construction shown may be 55 altered or omitted without departing from the spirit of this invention as defined by the following claims.
- I claim:
1. An air cleaner of the class described, 60 comprising a casing and a rotor journaled therein, said rotor being surmounted by and rigid with a hood provided with projecting fins, said casing being provided with a centrally located air inlet and an outlet, and 65 having an outlet for dirt near its outer edge.
2. An air cleaner of the class described, comprising a casing and a rotor journaled therein, said rotor being surmounted by and rigid with a hood of greater diameter than the rotor and being provided with project- 70 ing fins, said casing being provided with a centrally located air inlet and an outlet, and having an outlet for dirt near its outer edge.
3. An air cleaner of the class described, comprising a casing, a hood and rotor journaled therein, said hood being of conical form and of greater diameter than the rotor, and being provided with projecting fins, an inlet for air adjacent said hood, and an outlet for air near the rotor.
4. An air cleaner of the class described, comprising a casing having a floor, a disk spaced upwardly from the floor and provided with a central aperture, the edge of said disk terminating inwardly from the 85 casing, an air outlet centrally located in the floor, and a rotor mounted in the casing adjacent said outlet, said rotor being rigid with and surmounted by a conical hood, and said casing being provided with an inlet for air 90 above said hood.
5. An air cleaner of the class described comprising a casing having an inwardly projecting conduit and a rotor journaled in said casing adapted to be rotated by air 95 drawn through said casing, an impeller exterior of the conduit but rigid with said rotor for producing in said casing a vortex of greater diameter than said rotor, and means for collecting the dirt which is separated from the air by the centrifugal action 100 of said impeller.
6. An air cleaning device, comprising a casing with an inlet opening and an outlet opening through an inwardly projecting 105 conduit, and a rotatable element shaped and positioned to provide a restricted passage for air along the walls of the upper part of said casing and adapted to effect a whirling motion of the air drawn into said casing, said casing below said rotor being shaped and said inwardly projecting conduit being arranged relative thereto so as to provide a comparatively large unoccupied settling 110 area around said conduit below said rotatable element.
7. An air cleaner comprising a casing having an air inlet and an outlet, a rotor arranged to be driven by air flowing through said casing, and an impervious impeller carried by said rotor and arranged to form a partition located between said inlet and outlet, said impeller having a greater diameter than said rotor so as to produce a vortex of greater velocity than the lineal speed of said 115 rotor.
8. An air cleaner comprising a casing having an air inlet and an outlet, a rotor located in said outlet and arranged to be driven by air flowing through said casing,

and an impervious impeller carried by said rotor for producing within said casing a vortex of greater diameter than said rotor.

9. An air cleaner of the class described, comprising a casing and a rotor journaled therein, said rotor being surmounted by and rigid with a hood provided with projecting fins, said casing being provided with a cen-

trally located air inlet and an outlet opening through an inwardly projecting conduit, 10 and having an outlet for dirt near its outer edge.

Signed at Chicago this 2nd day of Oct. 1920.

JAMES P. QUAM.
